(57) **CLAIM**

The ornamental design for a wall washer light, as shown and described.

DESCRIPTION

FIG. 1 is a perspective view including a face, an end, and a side of the wall washer light;

FIG. 2 is a perspective view including an opposite face, an opposite end, and an opposite side of the wall washer light;

FIG. 3 is a plan view of the end of the wall washer light;

FIG. 4 is a plan view of the opposite end of the wall washer light.

FIG. 5 is a plan view of the opposite side of the wall washer light;

FIG. 6 is a plan view of the side of the wall washer light; FIG. 7 is a plan view of the face of the wall washer light; and,

FIG. 8 is a plan view of the opposite face of the wall washer light.

The broken lines showing in the drawings are for the purpose of illustrating portions of the wall washer light and form no part of the claimed design.
